UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

DESIGN FOR AN ELECTRIC LAMP.

48,964.

Specification for Design.

Patented May 2, 1916.

Application filed November 21, 1914. Serial No. 873,410. Term of patent 7 years.

To all whom it may concern:

Be it known that I, JOHN BERG, a citizen of the United States, residing at Chicago, in the county of Cook and State of Illinois, have invented a new, original, and ornamental Design for an Electric Lamp, of which the following is a specification, reference being had to the accompanying drawing, forming a part hereof.

Figure 1 is a front elevational view, and

Fig. 2 is a side elevational view of an electric lamp in accordance with my new design.

I claim:

The ornamental design for an electric lamp, as shown.

JOHN BERG.
